UNITED STATES PATENT OFFICE

JAMES W. JENNINGS, OF PROVIDENCE, RHODE ISLAND, ASSIGNOR TO QUAKER SILVER COMPANY, OF ATTLEBORO, MASSACHUSETTS, A CORPORATION OF MASSACHUSETTS

CONTAINER FOR COSMETICS, ETC.

Application filed December 27, 1929. Serial No. 416,796.

This invention relates to containers of the type suitable for cosmetics and having compartments for articles as well as for loose material and also to containers of this character which are adapted to rest on a table or other support and which are provided with covers for enclosing the contents when not in use.

The usefulness of containers of this character is due to some extent to the convenience with which access may be had to contained articles or materials, such as powder, powder puff, rouge, lipstick and the like, which are commonly used together or at about the same time. While the various items comprising the contents should be readily accessible they should also be compactly arranged so that the container need not be large and cumbersome to handle. When the contents are not being used it is desirable that they be enclosed to protect them from contamination by dust or other foreign matter and of course loose material, such as powder, should be kept separate from other objects. Moreover, the compartment for powder should be capable of presenting a sufficient area of this material to assure proper application thereof to the puff whether large or small quantities of powder are present.

Objects of the present invention are to improve the construction and arrangement of parts of a container of the class described; to provide a container capable of enclosing cosmetics in readily accessible and yet compactly arranged positions; to provide a container of this character capable of exposing an adequate area of powder when various amounts of this material are present; and also to provide a container of this class of simple, efficient and yet rugged and durable construction.

In accordance with the present invention a container of the class described may be provided with a lower compartment or basin for loose material, as for powder, and other objects, such as rouge, lipstick, and the like

may be carried by a shelf adapted to overhang the powder cavity and to be removable from this position so that substantially the entire upper surface of the powder may be exposed for application. In this way the contents may all be readily accessible and yet be compactly nested together so as to occupy minimum space.

Preferably the shelf and also a cover for enclosing the contents are hinged to the powder compartment and means are provided for preventing objects carried by the shelf from falling into the powder compartment and this is accomplished in a way not to interfere with the accessibility of these objects. The cover has an interior recess or cavity to accommodate a portion at least of the body of the puff when relatively large amounts of powder are in the powder compartment, thereby making it possible to close the cover at all times.

Another feature of this container resides in the construction of the basin or compartment for powder. The sides of this compartment are plane surfaces which meet in angles greater than right angles and these sides slope inwardly toward the center at an angle less than the angle of repose for powders suitable for cosmetic purposes. All powders of this class are crystalline and some powders such as talcum have flat plate crystals. Because of their crystalline character, these powders will adhere better to a flat sloping surface than to a concave surface. As the sides are inclined at an angle less than the angle of repose and are also flat surfaces such powders tend to remain in a state of equilibrium on these sloping sides even when only a small amount of powder is present and thus it is assured that under all conditions a large area of the contained powder will be exposed for application to the puff. By virtue of the fact that the sides meet in angles greater than right angles it is further assured that there will be no sharp corners or other pockets in which powder might be inaccessible.

In the drawing:

Fig. 1 is a top plan view of a container;

Fig. 2 is a top plan view of the container shown in Fig. 1 with the cover removed;

5 Fig. 4 is an end elevation of the container shown in Figs. 1 and 2;

Fig. 4 is an end elevation of the container shown in the preceding figures with parts broken away to show the construction;

10 Fig. 5 is a sectional elevation taken substantially along the line 5—5 of Fig. 3, but showing the cover in open position;

Figs. 6, 7 and 8 are detail views illustrating certain features of the invention.

15 The container selected for illustration comprises a body portion 10 mounted upon a base 11 by means of a pedestal 12 integrally connecting these parts. The body portion is hollowed to provide a basin or compartment 13 for cosmetics and a cover 14 is arranged to enclose cosmetics contained in the compartment.

20 The compartment is preferably in the form of a chamber having a bottom 16 and side walls 17, 18, 19 and an open top and the side walls are plane surfaces which slope inwardly to the bottom at an angle less than the angle of repose for crystalline powders such as are commonly used for these purposes. This arrangement assures that powder will remain in equilibrium upon sloping side walls even when only small quantities of powder are present. It thus becomes possible to expose a relatively large area of the contained powder for application to a puff or other means. As these powders are all crystalline and some such as talcum have flat plate crystals it is assured that the faces of the crystal will offer greater resistance to sliding down the plane surfaces of the side walls. For example if these walls were concave, plate-like or other crystals reposing thereon would contact with the concave surface only along the edges of the faces of the crystals and hence would offer 30 very little frictional resistance to sliding. By virtue of the fact however that the inner side walls are smoothly finished plane surfaces the crystals of these powders may rest with their flat surfaces directly against the plane surfaces of the walls and in this way offer a relatively high resistance to sliding movement.

35 The angle of repose for powder of this character will of course vary with different grades of powder but in general this angle will not be greater than approximately 60°. As the side walls slope inwardly at an angle less than 60° powder disposed thereon will not tend to fall away but will remain in 40 stable equilibrium for use. In order to avoid having sharp corners or crevices in which powder might become lodged so as to be relatively inaccessible, the side walls are arranged to meet each other in angles greater than 90° and hence powder disposed in the trough-like

depressions formed by these meeting sides will always be readily accessible for application to the puff. It will be apparent therefore that the various features thus far described provide for exposing a relatively large 45 surface area of powder when various amounts of this material are present thereby assuring proper application of the powder to the puff. Under some conditions of use the powder might tend to accumulate near the brim of the powder compartment and to fall over the sides thereof. For preventing 50 occurrences of this kind the brim of this compartment is provided with an inner marginal wall 21 (Fig. 5) which is substantially vertical so that should any powder come in contact therewith it will readily fall away from this vertical marginal portion.

55 In order to support other articles of cosmetics within the container and separate from the powder, a shelf 22 is disposed longitudinally along the rear edge of the container and adapted to rest within the vertical marginal wall 21. This shelf is provided with bearings 23 (Fig. 2) by which it is mounted to pivot upon a hinge pin 24 (Figs. 4 and 5) mounted in bosses 26, 26' on the rear top edge of the body portion 10 and spaced to receive the intermediate and end portions of the hinge pin. As the shelf is relatively light the bearings therefor are spaced closely adjacent the intermediate boss 26' of the hinge pin and the cover being relatively heavy is provided with bearings 27 by which it is mounted on the hinge pin between the bearings 23 for the shelf and the end bosses 26 for this pin. This arrangement provides a durable and yet simple construction for operatively connecting these parts. Adjacent the ends of the shelf the latter is provided with cylindrical 60 depressions 28 the lower portions of which are turned inwardly to provide annular supporting ledges 29 upon which cakes of rouge 31 may rest. The cylindrical portions of these depressions are of proper size to receive rouge cakes and the annular ledges extend inwardly only a relatively short distance leaving a central opening 32 through which a finger may be inserted to push the cake upwardly to remove the same. As the shelf is turned upwardly on its hinges to permit access to the lower or powder compartment these cakes of rouge might under some conditions tend to fall out and to prevent this, clips 33 are affixed to the shelf on the sides of 65 the depressions adjacent to the hinges for releasably holding these cakes therein.

70 The shelf is also provided with an elongate depression 34 (Fig. 2) disposed longitudinally between the cylindrical depressions and relatively close to the hinge pin or pivotal axis of the shelf. This elongate depression is of a size to receive some elongate article such as a lipstick 36 and is of a depth to hold the lipstick slightly above the surface 75

of the shelf so that the latter may be grasped readily by the fingers. This elongate depression is formed with substantially straight longitudinal side walls 37 so that the lipstick may be readily removable therefrom. This depression is also spaced a sufficient distance from the hinges to provide space for the fingers of the user when picking up or inserting lipstick. As the depression 34 depends from the under side of the shelf, it will be seen from Fig. 5 that when the shelf is in its upper or raised position a vertical line through the center of gravity of the lipstick or other contained article will fall within the depression and to the left of the hinge pin thus tending to maintain the lipstick in stable equilibrium. The central portion of the front edge of the shelf is cut away to provide a recess 38 (Fig. 2) for the puff and 20 through which the puff may be grasped by the fingers.

In order that the device may be in relatively stable equilibrium while in use means are provided for limiting the opening movement of the cover and for supporting this cover in a substantially vertical open position. For this purpose the rear outer edge of the body portion 10 is provided with a longitudinal ledge 41 which is engageable with a similar ledge 42 on the cover when the latter is in a substantially vertical open position so that the cover may rest upon the lower ledge. In this position the center of gravity of the cover falls nearly within the base line and 35 considering the weight of the contents, the container is in relatively stable equilibrium when the cover is open. When the shelf is raised to its vertical position the outer ends thereof abut the adjacent edges 43 (Figs. 6, 7, 40 8) of the cover and thus further movement of the shelf is prevented. The cover is provided with an inner recess 44 adapted to extend above the central cut-away portion of the shelf and above the lower compartment 45 to provide space for accommodating the puff so as to permit complete closing of the cover when a relatively large supply of powder is present.

As the elongate depression provided in the shelf for lipstick or other elongate article is provided with straight sides it will be apparent that such article might be thrown out of this depression under some conditions as for example if the shelf were raised abruptly. While abutment means might be provided on the cover for engaging the lipstick to hold the latter in the depression I prefer to avoid a construction of this character because any abutment means would necessarily 55 be close to the elongate depression and it would be difficult to provide room for the fingers of a person using the lipstick. On the other hand it is undesirable to space the elongate depression at a large radius from the hinge as the centrifugal force incident to

opening or raising the shelf might then become a material factor in disturbing the equilibrium of the contained lipstick. In order that this lipstick may therefore be readily accessible, the adjacent inner wall 46 of the cover is inclined outwardly from the hinges (when the cover is in vertical position) and this inner wall of the cover is inclined at an angle such that should the lipstick be thrown against this wall the inclination thereof will not only cause the stick to descend upon the portion of the shelf between the elongate depression and the hinges but will also tip the stick or like article to an unstable position on the shelf, thereby causing the stick to fall back into the depression, thus preserving an orderly arrangement without in any way interfering with the accessibility of the lipstick. It will be understood of course that the elongate depression in the shelf is spaced in sufficient proximity to the hinges to allow the lipstick to fall therein under the conditions just described. Should the lipstick be thrown out against the cover in the manner just described the stick will turn through an angle (Fig. 6) of approximately 180 degrees from the position which it occupied while reposing in the depression when the shelf was in its lowered or horizontal position. As the dislodged lipstick descends to a position of unstable equilibrium (Fig. 7) on the edge of the shelf it is caused to turn or rock in the opposite direction so that it finally lands in the depressions (Fig. 8) with the same side up as before it was thrown out. This is important when the lipstick is provided with a knob 48 or other protuberance by which it may be picked up as the knob 48 is always disposed upwardly where it may be of use.

The upper or exterior surface of the cover is formed with sides 49 which slope upwardly from the outer edges thereof to a central portion for guiding the fingers of a user to the handle 51 mounted at the apices of the sloping sides. This handle is preferably in the form of a vertically extending flat plate having notches 52 cut through the plate and similarly disposed in opposite edges thereof for engagement by the fingers of a user. The front and rear faces of this plate also have embossments 53 which may be of a decorative character and serve to provide a good grip on the faces of the handle. The outer side walls 54 of the body portion are arranged to slope downwardly and inwardly to the pedestal so that the cover and body portion may be grasped readily in the hand and at the same time the cover may be held closed while the container is being moved from one position to another.

While only one form of this invention has been shown in the drawings, it will be apparent that various modifications thereof will occur to those skilled in the art to which

this invention appertains and that the invention is not limited except as indicated by the appended claims.

I claim:

1. In a device of the class described, the combination of a compartment for powder, said compartment comprising a bottom and side walls, a shelf and a cover hinged to a side wall, the shelf being adapted to extend in overhanging relation over only a portion of the compartment and the cover having an interior recess whereby a puff may be disposed on powder in the compartment and may project upwardly above the side walls and into the recess in the cover without interfering with the complete closing of the cover.

2. The combination as set forth in claim 1, and means for holding the cover in a substantially vertical, open position, and thereby obviating putting the device in a condition of unstable equilibrium when the cover is opened.

3. In a device of the class described, a compartment for powder, said compartment comprising a bottom and side walls, a shelf and a cover hinged to a side wall, the cover being adapted to enclose the shelf and to fit the side walls of the compartment, the shelf having depressions for cosmetics, and clips projecting above some of the depressions for retaining the cosmetics.

4. The combination as set forth in claim 3, wherein the shelf has depressed annular ledges adjacent the ends thereof for rouge, and the retaining clips project above these ledges for retaining the rouge.

5. The combination as set forth in claim 3, wherein the shelf has depressed annular ledges adjacent the ends thereof for supporting rouge and has openings within the ledges and through the shelf whereby the rouge may be removed, the shelf having an elongated depression disposed longitudinally thereof and between the depressed annular ledges.

6. In a device of the class described, a compartment comprising a bottom and side walls and having an open top, the inner sides of the side walls being plane surfaces inclined inwardly toward the bottom and meeting each other in angles greater than ninety degrees.

7. In a device of the class described, a compartment for powder, said compartment comprising a bottom and side walls, the inner sides of the side walls being plane surfaces inclined inwardly to the bottom at an angle less than the angle of repose for crystalline powder.

8. A container of the class described, comprising a body portion having a compartment for powder, a cover for the compartment, the cover being mounted to pivot in the body portion, a handle on the upper surface of the cover, said handle comprising a sub-

stantially flat, vertically disposed plate having notches extending through the plate and in the outer edges thereof, said notches being similarly disposed and of sufficient size to accommodate the fingers of an operator.

9. A container of the class described comprising a body portion having a lower compartment therein, a shelf having an elongate depression therein for holding an elongate article, means for supporting the shelf for pivotal motion from a substantially horizontal position above the lower compartment to a substantially vertical position at one side of the lower compartment, a cover for enclosing the shelf and for closing the lower compartment, means for supporting the cover for movement to open and to closed positions, the cover having an inner surface disposed at a sufficient angle when the cover is open to tip the elongate article disposed thereagainst to an unstable position on the shelf when the latter is in substantially horizontal position, the elongate depression in the shelf being sufficiently near to said inner surface of the cover to allow the elongate article to fall therein.

10. The combination as set forth in claim 9, and an elongate article receivable in said elongate depression in said shelf, said elongate depression having sufficient depth so that a vertical line through the center of gravity of the elongate article will be disposed on the under side of the shelf when the latter is in substantially vertical position.

11. The combination as set forth in claim 9, and an elongate article receivable in the elongate depression in the shelf, the elongate depression having substantially straight sides and being of a depth to hold the elongate article slightly above the upper surface of the shelf, whereby the elongate article may be readily accessible.

12. The combination as set forth in claim 9, and means providing abutments on the cover and on the body portion, said abutments being engageable for limiting the opening of the cover.

13. The combination as set forth in claim 9, and means providing abutments on the cover and on the body portion, said abutments being engageable for limiting the opening of the cover and being positioned for holding the cover in a substantially vertical position when open, whereby the container may be more stable when the cover is open.

14. A container of the class described, comprising a body portion having a compartment therein, a hinge pin mounted on one side of the body portion, a shelf having an elongate depression therein for holding an elongate article, a cover for enclosing the shelf and for closing the compartment, the cover and the shelf being mounted to pivot on the hinge pin, means for supporting the cover in open position, the shelf being mov-

able from a substantially horizontal position above the compartment to a substantially vertical position at one side of the compartment, the cover having an inner surface disposed at a sufficient angle when the cover is open to tip an elongate article disposed thereagainst to an unstable position on the shelf when the latter is in a substantially horizontal position, the elongate depression on the shelf being in sufficient proximity to said inner surface of the cover to allow the elongate article to fall into the depression.

5 Signed by me at Attleboro, Mass., this twenty-fourth day of December, 1929.
